CLAIM

The ornamental design for a shower handle assembly, as shown and described.

DESCRIPTION

FIG. 1 is a front perspective view of a shower handle assembly showing our new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The uneven length broken line immediately adjacent to the photographic region represents an unclaimed boundary of the design. The even length broken line showing of the remainder of the shower handle assembly is for environmental purposes only and forms no part of the claimed design.
